UNITED STATES PATENT OFFICE

158,420

CARD GAME SCORE INDICATING DEVICE

Hazen Mercer Sullivan, Chicago, Ill.

Application March 18, 1948, Serial No. 145,197

Term of patent 3½ years

(Cl. D34—13)

To all whom it may concern:

Be it known that I, Hazen Mercer Sullivan, a citizen of the United States, residing in Chicago, in the county of Cook and State of Illinois, have invented a new, original, and ornamental Design for a Card Game Score Indicating Device, of which the following is a specification, reference being had to the accompanying drawing, forming a part thereof.

Fig. 1 is a perspective view of the device;

Fig. 2 is a front view;

Fig. 3 is a side view taken from the left hand side of Fig. 2; and

Fig. 4 is a rear view on a slightly smaller scale than Figs. 2 and 3.

The dominant features of my new design are shown in solid lines in the drawing.

I claim:

The ornamental design for a card game score indicating device, substantially as shown and described.

HAZEN MERCER SULLIVAN.
